Primary Examiner — Ian Simmons*Assistant Examiner* — Carissa C Fitts(74) *Attorney, Agent, or Firm* — Thomas E. Lees, LLC(57) **CLAIM**

The ornamental design for a utility work light, as shown and described.

DESCRIPTION

FIG. 1 is a top plan view of the utility work light;
FIG. 2 is a front side elevational view of the utility work light;
FIG. 3 is a rear side elevational view of the utility work light;
FIG. 4 is a bottom plan view of the utility work light;
FIG. 5 is a left end elevational view of the utility work light;
FIG. 6 is a right end elevational of the utility work light;
FIG. 7 is a perspective view of the utility work light with the left end forward; and,
FIG. 8 is a perspective view of the utility work light with the right end forward.
The broken line showing is for environmental purposes only and forms no part of the claimed design.

1 Claim, 7 Drawing Sheets(56)
